(57) **CLAIM**

The ornamental design for air sensor, as shown and described.

DESCRIPTION

FIG. 1 is a front perspective view of an air sensor in accordance with the new design.

FIG. 2 is rear perspective view thereof.

FIG. 3 is a top elevation view thereof.

FIG. 4 is a bottom elevation view thereof.

FIG. 5 is a front elevation view thereof.

FIG. 6 is a rear elevation view thereof.

FIG. 7 is a side elevation view thereof; and,

FIG. 8 is an alternate side elevation view thereof, showing the side opposing that shown in FIG. 7.

The broken lines shown in the drawings are only provided to illustrate the environment of the design and form no part of the claimed design.

1 Claim, 6 Drawing Sheets

FIG. 3

FIG. 4

FIG. 5

FIG. 6

FIG. 7

FIG. 8
